UNITED STATES PATENT OFFICE

ESMOND P. G. WRIGHT, OF CROYDON, ENGLAND, ASSIGNOR TO WESTERN ELECTRIC COMPANY, INCORPORATED, OF NEW YORK, N. Y., A CORPORATION OF NEW YORK

TELEPHONE SYSTEM

Application filed September 20, 1929, Serial No. 393,872, and in Great Britain December 20, 1928.

This invention relates to automatic and semi-automatic telephone exchange systems and more particularly to arrangements in which a wanted line designation is stored in 5 registering apparatus located at one office and is transmitted over a selected junction line to another office.

Such an arrangement finds application, for example, in systems in which it is required to 10 transmit over a junction extending from an automatic office to a manual office, voice current signals characteristic of a wanted line designation whereby a manual operator at the last-mentioned office is informed verbally 15 of the number of a wanted party. More specifically, the invention contemplates means effective if successive digits of a wanted line designation are of the same numerical value to translate the designation into voice current signals, the verbal equivalents of which 20 are different from the verbal equivalents of the recorded digits.

The invention finds one specific embodiment in a system in which the conversation 25 switches are set under the control of control circuits, each common to a group of conversation switches but individual to the switching stage to which the group belongs. Such a system is fully disclosed in British Patent 324,982, to which reference is hereby made 30 for a description of the circuits and operation not disclosed in the present application and which are not essential to an understanding thereof. A general reference is also 35 made to U. S. Patent 1,678,103, granted to H. C. Caverly July 24, 1928, for one form of annunciator mechanism for generating voice current signals.

Referring now to the accompanying drawings, 40

Fig. 1 shows to the left of the broken line a conversation group finder switch of the no-normal step-by-step single-motion type having access to a plurality of groups of 45 junctions. At the right of the broken line is shown the end of the junction at the manual office together with an operator's cord circuit at that office.

Fig. 2 indicates a control circuit common 50 to a plurality of conversation finders com-

prising a single-motion homing switch R1 having wipers and banks 1 to 9, and a single-motion non-homing switch R2 having wipers and banks C, T, M. The first positions of the switch R1 are used for controlling the 55 operation of the switch R2 and, accordingly, marking wires extend from the bank 9 to groups of contacts in the bank C corresponding to the groups of outgoing junctions. The subsequent positions of the switch R1 are 60 used for associating the control and annunciator circuits with a predetermined conversation finder. Marking wires also extend between the bank M of the switch R2 and the banks of the associated conversation finders. 65 The terminals of the test bank T of the switch R2 are multiplied to corresponding terminals of the banks H of the associated conversation finders. The finder and its control circuit is designed to be taken into 70 use from a preceding group selecting stage of the kind fully described in the above identified British patent.

Figs. 3 and 4 indicate an annunciator circuit which is permanently associated with the 75 control circuit shown in Fig. 1 over wires 101 . . . 116.

Fig. 5 indicates the proper arrangement of Figs. 1 to 4.

In the establishment of a connection a calling subscriber becomes connected by means of first and second line finders with a group finder with which is associated an idle control circuit. This control circuit includes two switches, a control switch and a by-pass 80 switch. The control switch is set in accordance with the first digit dialed, after which the by-pass switch hunts for an idle second group finder in the group marked by the control switch. This second group finder may 85 be the finder shown in Fig. 1 of the present disclosure or other similar group finders may intervene. At the same time the control switch hunts for the first group finder with which the subscriber's line has been connected 90 and which will replace the by-pass switch. The group finder is then set on the trunk selected by the by-pass switch. Meanwhile the second digit is passing over the by-pass switch to the control circuit shown in Fig. 1. This 95 100

control circuit functions in a manner similar to the control circuit of the first group finder but since this second group finder has access to trunks outgoing to a manual office the remaining digits are recorded on relay registers in the control circuit and when the manual operator responds are transmitted in the form of voice current signals to that operator.

10 The machine for generating voice current signals may be of any suitable form such as a phonograph record, photographic film in combination with a light valve, etc. The digits 1 to zero together with the letters for 15 designating the party lines, if party lines are used, and such other suitable words as "double" or "tandem", etc. are recorded. Means for picking up the sound generated by these records and amplifying them is provided for 20 each record and the control circuit is arranged so that the setting of a control circuit register in response to a particular digit will provide a circuit for causing the transmission of the voice current signal corresponding to 25 that digit to the operator at the distant office. In case the thousands and hundreds digits are the same or the tens and units digits are the same, the thousands or tens register is reset by operating all of the relays 30 of that register and the word "double" is transmitted in place of the digit recorded. Other words may, of course, be transmitted to care for other conditions. The generating machine carries a pair of pick-up cams so 35 that the circuit for transmitting the digits can be closed only at the beginning of the digit.

A call will now be traced in detail.

The selector repeater circuit with its associated control and announcer circuit is tested 40 through the wire T, BS1, t4, wire 111, wiper and home contact of the bank 9 of the switch R3, wire 114, bank contact and wiper of the bank 9 of the switch R1, t9, b4, to resistance and battery. When the by-pass 45 switch at the preceding switching stage switches through in the manner fully described in the above identified British patent over the by-pass conductors BP- and BP+, the relay A is operated and closes an obvious circuit 50 for relay B through a2. Relay B places ground on the test wire at b1 and removes the battery from the test wire at b4. At the first impulse, relay A releases but relay B 55 being of the slow release type remains operated and completes a circuit for the magnet R1, through h4, e5, b3, winding of relay C, a1 to ground. At the end of the impulse, relay A reoperates and the switch R1 steps into 60 position 2. In this way the switch R1 takes one step for each impulse and relay C remains operated, being of the slow to release type.

At the end of the impulsion, when relay C releases, a circuit is completed for relay E 65 through c2, the bank contact and wiper of the

bank 3 of the switch R1, interrupter springs, and ground at t6. Relay E locks up through e8 to ground at b1. Relay E also completes the driving circuit for the switch R2 through its interrupter springs, h2, e3, p2, g2, b1 to ground. Ground at b5 is extended to the wiper 9 of the switch R1 via t9 and depending upon the position in which the switch R1 has come to rest it will be extended to a group of contacts of the bank C of the switch R2. When the wipers of the switch R2 are passing over this group of contacts the ground from b5 will be extended over g4 through the winding of relay P, h9 to the bank T of the switch R2 and if this switch passes over a free contact which is characterized by a battery potential, relay P will operate, opening the driving circuit at p2 and completing a circuit via g2, b1 for relay H at p1. Relay H will lock through h1, t1 to ground at e1. The operation of relay H places a ground potential through h8 on the test wiper T to mark the junction busy.

Meanwhile a second series of impulses may be in the course of being received, each impulse operating the magnet R3 through the wire 105, e6, e4, b3, winding of relay C and a1 to ground. At the end of impulsing, relay C releases and completes a circuit from ground on the bank contacts of the bank 1 of the switch R3 to wire 102, c1, wire 103, to the wipers of the banks 2, 3, 4 and 5 of the switch R3. The position of the switch R3 will determine which of the relays MA, MB, MC and MD will be operated by this circuit. If, for example, the digit 7 is dialed only the relay MA will operate whereas if the digit 1 is dialed only relay MB will operate. In either case the relay will lock up over its second winding to ground through the wire 101, e2, and the relay ZA which is slow to operate will operate in series with the operating windings of the storing relays. The relay ZA will complete the following circuit for the magnet R3 through the wire 105, e6, e4, b3, winding of relay C, wire 108, za1, za2, contacts and wiper of the bank 7 of the switch R3, interrupter springs to ground. The contacts of the bank 7 are multiplied together to cause the switch to step forward until the switch R3 reaches position 12. In this position the ground connection to the bank contacts of the bank 1 is not connected so that when relay C releases there is no ground on the wipers of the banks 2, 3, 4 and 5. In a similar way, when the next set of impulses is received the switch R3 steps a number of steps corresponding to the digit dialed and when relay C releases a certain combination of the relays CA, CB, CC and CD together with relay ZA are operated and the switch R3 is caused to step forward to position 23. In this position a circuit will be extended to the wipers 2, 3, 4 and 5 if the combination of relays which have been operated to store the thousands 130

digit corresponds exactly with the relays operated to store the hundreds digit. This circuit may be traced from ground through the interrupter springs to the wiper of the switch R3 having access to bank 7, bank contact of position 23 of bank 7, contact 8 or 9 of relays CD, MD, MC, CC, CB, MB, contacts 4 or 5 of the relays MA and CA to the wipers 2, 3, 4 and 5 which in position 23 are connected to the relays MA, MB, MC and MD which will cause the operation of any of these relays which are in a normal condition. In a similar way the tens impulses will cause the operation of a combination of the relays DA, DB, DC, DD and the units impulses will be stored on the relays UA, UB, UC, UD, the switch R3 going to positions 34 and 45 respectively after the reception of the tens and units digits. In position 45 a circuit is again completed if the tens and units digits are similar to cause the operation of any of the relays DA, DB, DC and DD which were in a normal condition. This circuit is completed over contacts 4 or 5 of the relays UA and DA and contacts 8 or 9 of the relays DB, UB, UC, DC, DD, UD.

When the relay H, Fig. 2, operated a circuit was completed for the magnet R1 through h3, interrupter springs and t6 to ground. This circuit causes the switch R1 to step until the relay T operates over the wiper and contact of bank 2 to ground on the H wire of the associated predetermined finder through contacts bs7. When relay T operates it opens at t6 to the driving circuit of the switch R1, opens at t4 the circuit holding the previous control circuit and closes a locking circuit at t5 which maintains a ground potential on the H wire of the selector to maintain the previous switching relays operated. Contacts t3 complete the bypass through the wiper and contact of bank 1 of the switch R1 via bs5 and ds3. The positive side of the loop is replaced through ds2 and bs3 to ground. Contacts t7 complete a circuit for the magnet SR through h7, t7, m1 and the wiper and contact of the bank 6, a spark quenching combination being introduced over the bank 5. The finder is caused to step forward until the wiper M reaches a position multiplied to the bank M of the switch R2 in which position the circuit for the relay M is completed at t8. When relay M operates the left hand winding of relay I, Fig. 3, is bridged across the outgoing + and - wires and the following loop circuit is completed: ground, h2, Fig. 1, + line, bs11, bank 8 of switch R1, m2, wire 110, left hand winding of relay I wire 109, bank 7 of switch R1, bs9, - line, h1, relay L to battery. Relay L lights the calling lamp c2, but relay I does not respond due to the high resistance of relay L. When the operator plugs in, the sleeve relay K operates, disconnects the line relay L at h1, h2 and extinguishes the lamp C2 at h3. The left hand winding of relay N is substituted for relay L but this winding is of sufficiently high resistance also to prevent the operation of relay I. When the operator throws her listening key the relay N is short-circuited and the operator's circuit is introduced in the loop over relay I, which now operates and prepares the circuit for relay SA through i2 and wire 214 to a pull-up cam carried by the call announcer machine. Each time this interrupter closes, the relay SA operates and a moment later locks for a short interval over wire 213 and a second interrupter also carried by the machine. Both these cams are connected to ground. When the switch R3 reaches position 45 if it has not already done so, a circuit is completed for the magnet of this switch R3 over the wire 105, e6, wire 104, sa3, bank contacts and wiper of the bank 7 of the switch R3 and through the interrupter springs to ground. The call announcer machine which is revolving continuously causes one operation of the relay SA for each announcing period and consequently the switch R3 steps home at the rate of one step for each announcing period. When the switch R3 reaches position 48 a circuit is completed from the right hand winding of the relay I which is connected to battery, the wiper and bank contact of the bank 8 of the switch R3 to the chain of relay contacts either through ma2 or ma3 which have been set in operation by the first of the four digits received by the switch R3. If the digit dialed was 1 connection will be made with the wire 201, if the digit was 7 connection will be made with the wire 207, if the digit was 0 connection will be made with the wire 210 and if the first two digits were the same all the relays of the series would be operated and connection would be made with the wire 211. As previously described these eleven wires run to pick-ups associated with the call announcer machine from which each of the wires 201 to 210 will receive the corresponding number one to ten or zero. The pick-up connected to wire 211 will receive the word "double" so that if the thousands and hundreds or tens and units digits are the same the word "double" will be sent out in place of a thousands or tens digit followed by the proper hundreds or units digit. Each of these eleven pick-ups has an associated amplifier circuit of any suitable kind. The current changes in the primary winding of the relay I are induced into the secondary winding thereby being repeated over the junction to the manual end. In position 49 a similar circuit will be completed which is not shown in the illustration for the number corresponding to the second set of impulses received from the switch R3. In position 50 there is no connection and the time period will cause a break between the first two and

last two digits in order to simulate the manual practice of pausing between certain digits. In position 51 the pick-ups are again connected through the contacts of the relays 5 representing the tens digit and in the home position a similar set of contacts representing the units digit are connected through contacts *ra2*.

It will be seen that relay RA becomes operated during the first operation of the relay 10 SA and remains locked up over *ra1*, wire 101 and *e2*. When relay SA operates in a home position a circuit is completed over interrupter springs, wiper and contact of bank 7, 15 *sa2*, wire 107, *h5*, wiper and bank contact of the bank 4 of the switch R1, *as2*, to the relay BS and battery. Relay BS operates, closes the circuit for relay AS over the calling loop. Relay AS closes at *as1* a locking 20 circuit for relay BS which disconnects the control and annunciator circuit. All the operated relays in the control and annunciator circuit now release and a restoring circuit is closed for the switch R1 via *h4*, *e5*, *b2*, 25 off normal bank 3 and interrupter springs to ground at *t6*. Relay BS also introduces the impedances IS and the upper winding of shunt field relay DS in the forward loop at *bs8* and *bs10* and opens the circuit from 30 the announcer at *bs9* and *bs11*. Contacts *bs6* provide a ground potential on the hold wire H to maintain the previous switching relays. Contacts *bs12* apply a ground potential to the H wiper forward to maintain the 35 junction in an engaged condition. When the called subscriber answers, the current fed out from the manual end is reversed causing the operation of the relay DS which in turn reverses the current in the calling subscriber's 40 circuit thereby giving a metering signal. When the calling subscriber hangs up at the end of the conversation the relay AS restores and after a period relay BS releases 45 also removing earth from the hold wires and opening the circuit for the lower winding of relay DS.

If the call is to be tandemed through one manual office to a second office after the 50 switch R1 has responded to a particular digit indicative of a tandem call, the tandem relay TA will be operated through *h10*, *c3*, *ta3*, bank contact and wiper of the bank 9 of the switch R1, *t9*, *b5* to ground. The operation of relay TA which will lock up over *ta4*, wire 55 116, *ra4*, to ground, will transfer at *ta2* the marking ground from the bank contact on which switch R1 is resting to the group of junctions leading direct to the office through which the call is to be tandemed. In consequence if a call is made for an office with a code discrimination 4 and is to be tandemed 60 through an office with a code discrimination 3, the operation of relay TA will cause the 3rd and 4th contacts on the bank 9 of the switch R1 to be joined together. The switch 65

R2 will therefore proceed to find an idle junction to the tandem office and the call will proceed as already described until the switch R3 reaches position 46. It will be seen that in this position a circuit is completed for the right hand winding of relay I through *ta5*, if this relay TA is operated, to the wire 212 which is associated with the pick-up giving a "tandem" signal which will be repeated in the same way as the numerical portion of the call to the manual operator. Contacts *ta1* will prevent the switch R3 from stepping forward until the TA relay has released. When relay TA operated the locking circuit of relay TA was made dependent upon relay I and this relay will fall back as soon as the operator at the tandem exchange restores her listening key LK (thereby reintroducing the left hand winding of relay N into the loop) and extends the call to the second operator. The relay N also at *n1* closes the forward loop to the second operator so that when the distant operator throws her listening key relay Q will operate, short circuiting the high resistance left hand winding of relay N with its low resistance right hand winding and thereby causing the re-energization of relay I in the announcer. When relay I reoperates the circuit will be again closed for relay SA in conjunction with the call announcer cams and the numbers stored in the announcer will be sent out. Relay M is a supervisory relay which will be operated when the called subscriber replies and its contacts *m1*, *m2* will reverse the direction of current to the automatic exchange.

If tandem calls are required to be made over other groups of junctions the circuit is modified so that in positions of the switch R1 corresponding to the code discriminations of the distant offices, circuits are completed over the bank 9 for the relay TA which will be provided with additional contacts over which pairs of terminals of the bank 9 are joined together so that the marking ground is transferred to the control terminal which is associated with the group of junctions leading to the office through which the call is to be tandemed.

If all the junctions in the required group are engaged the switch R2 will continue testing during the time the first three digits are being received in the R3 switch which on reaching position 34 will close a circuit over the wiper and bank contact of the bank 7, the wire 115, *h6* to relay G which on operating will lock up through *g5* to ground at *b1*, open the testing circuit of relay P at *g4*, open the driving circuit of the magnet R2 at *g2*, connect busy tone over lead *Bt* to the calling subscriber at *g1*, and connect the magnet R1 through *g3* and the interrupter springs to ground at *t6* causing that switch to associate the control with the predetermined finder. When the subscriber hangs up re-

lays A and B cause the connection to break down.

It is apparent that the present invention contemplates such modifications as expansion to care for three like digits, or variation to announce the words "hundred" and "thousand" commonly used in the United States.

What is claimed is:

1. In a telephone system, a selection control device, an operator's position, means for recording the elements of a telephone designation in said device, means for generating voice current signals, means under control of said recording means and said generating means for transmitting voice current signals to said operator's position, and means for translating one or more of the recorded elements into voice current signals, the verbal equivalents of which are different from the verbal equivalents of the recorded elements.

2. In a telephone system, a selection control device, an operator's position, means for recording the digits of a telephone designation in said device, means for generating voice current signals, means under control of said recording means and said generating means for transmitting voice current signals to said operator's position, and means for translating one or more of the recorded digits into voice current signals, the verbal equivalents of which are different from the verbal equivalents of the recorded digits, said translation being determined by the values of two or more of said recorded digits.

3. In a telephone system, a selection control device, an operator's position, means for recording the digits of a telephone designation in said device, means for generating voice current signals, means under control of said recording means and said generating means for transmitting voice current signals to said operator's position, and means effective if two successive recorded digits are of like value to translate the first of said digits into a voice current signal to indicate that the two digits are of the same value.

4. In a telephone system, a selection control device, an operator's position, means for recording the digits of a telephone designation in said device, means for generating voice current signals, means under control of said recording means and said generating means for transmitting voice current signals to said operator's position, and means effective if two successive recorded digits are of like value to translate the first of said digits into a voice current signal equivalent to the word "double" to indicate that the two digits are of the same value.

5. In a telephone system, a selection control device, an operator's position, means responsive to the office designating portion of a wanted number, means responsive to the numerical portion of a wanted number, means for automatically transforming the

numerical portion of said wanted number into voice current signals characteristic of said numerical portion and transmitting said voice current signals to such operator's position, and means effective if the office designating portion of the wanted number is indicative of a tandem call to transmit only a single predetermined voice current signal to said operator's position.

6. In a telephone system, an operator's position, a selection control device, means for recording the digits of a telephone designation in said device, said recording means comprising a switch adapted to respond successively to the numerical digits of said telephone designation and a plurality of groups of storage relays operated over the contacts of said switch, means for generating voice current signals, and means under the control of said storage relays for transmitting voice current signals characteristic of said telephone designation to said operator's position.

7. In a telephone system, an operator's position, a selection control device, means for recording the digits of a telephone designation in said device, said recording means comprising a switch adapted to respond successively to the numerical digits of said telephone designation and a plurality of groups of storage relays operated over the contacts of said switch, means for generating voice current signals, means under the control of said storage relays for preparing circuits for transmitting voice current signals characteristic of said telephone designation to said operator's position, and means for advancing said switch to successively complete said prepared circuits.

8. In a telephone system, an operator's position, a selection control device, means for recording the digits of a telephone designation in said device, said recording means comprising a switch adapted to respond successively to the numerical digits of said telephone designation, a plurality of groups of storage relays operated over the contacts of said switch, and means for advancing said switch to an intermediate position following its response to each digit, means for generating voice current signals, and means under the control of said storage relays for transmitting voice current signals characteristic of said telephone designation to said operator's position.

9. In a telephone system, an operator's position, a selection control device, means for recording the digits of a telephone designation in said device, said recording means comprising a switch adapted to respond successively to the numerical digits of said telephone designation and a plurality of groups of storage relays operated over the contacts of said switch, means for advancing said switch to an intermediate position following the response to each digit, means for gener-

ating voice current signals, means under the control of said storage relays for transmitting voice current signals characteristic of said telephone designation to said operator's 5 position, and means effective in certain of said intermediate positions to determine whether the preceding pair of stored digits are of the same value.

10. In a telephone system, an operator's 10 position, a selection control device, means for recording the digits of a telephone designation in said device, said recording means comprising a switch adapted to respond successively to the numerical digits of said telephone 15 designation and a plurality of groups of storage relays operated over the contacts of said switch, means for advancing said switch to an intermediate position following its response to each digit, means effective in 20 certain of said intermediate positions to test whether the preceding pair of stored digits are of the same value, means for generating voice current signals, means under the control of said storage relays for transmitting 25 voice current signals characteristic of the digits of said telephone designation to said operator's position, and means responsive to said testing means to translate certain of said digits into voice current signals, the verbal 30 equivalents of which are different from the verbal equivalents of the recorded digits.

11. In a telephone system, an operator's position, a selection control device, means for recording the digits of a telephone designation 35 in said device, said recording means comprising a switch adapted to respond successively to the numerical digits of said telephone designation and a plurality of groups of storage relays operated over the contacts of said switch, means for advancing said switch to an intermediate position following its response to each digit, means effective in 40 certain of said intermediate positions to test whether the preceding pair of stored digits are of the same value, means for generating voice current signals, means under the control of said storage relays for transmitting voice current signals characteristic of the digits of said telephone designation to said 45 operator's position, and means responsive to said testing means to operate additional storage relays, whereby certain of said digits are translated into voice current signals, the verbal equivalents of which are different from 50 the verbal equivalents of the recorded digits.

In witness whereof, I hereunto subscribe my name this 20th day of August, 1929.

ESMOND P. G. WRIGHT.
